US00D801943S

(12) **United States Design Patent** (10) Patent No.: **US D801,943 S**
Cho et al. (45) Date of Patent: ** *Nov. 7, 2017

(54) **MULTIMEDIA PHONE**

(71) Applicant: **Meizu Technology Co., Ltd.**, Zhuhai (CN)

(72) Inventors: **Youngsu Cho**, Zhuhai (CN); **Yongxiang Bai**, Zhuhai (CN); **Xiuzhang Huang**, Zhuhai (CN)

(73) Assignee: **Meizu Technology Co., Ltd.**, Zhuhai (CN)

(*) Notice: This patent is subject to a terminal disclaimer.

(**) Term: **14 Years**

(21) Appl. No.: **29/508,032**

(22) Filed: **Nov. 2, 2014**

(30) **Foreign Application Priority Data**

May 20, 2014 (CN) 2014 3 0140629
